UNITED STATES PATENT OFFICE.

WILLIAM H. DOBLE, OF QUINCY, MASSACHUSETTS.

MACHINE FOR CLOSING AND SEALING THE ENDS OF CARTONS.

SPECIFICATION forming part of Letters Patent No. 787,877, dated April 18, 1905.

Application filed January 4, 1904. Serial No. 187,629.

To all whom it may concern:

Be it known that I, WILLIAM H. DOBLE, of Quincy, in the county of Norfolk and State of Massachusetts, have invented certain new and useful Improvements in Machines for Closing and Sealing the Ends of Cartons, of which the following is a specification:

The object of the present invention is to provide a machine to automatically close and seal the flaps at the top end of the carton after the carton is filled.

The invention is specially intended to be employed in combination with a machine for filling cartons, especially where the operation of the filling-machine is dependent upon the tipping of the scale.

The invention will now be fully described by reference to the accompanying drawings, and the novel features thereof will be particularly pointed out at the close of the specification.

In the drawings, Figure 1 is a plan of a machine embodying the invention. Fig. 2 is a side elevation viewed from the right of Fig. 1. Fig. 3 is an end elevation viewed from the left of Fig. 2. Fig. 4 is a detail plan of the package-moving fingers and their operating mechanism. Fig. 5 is a detail plan of the parts shown in Fig. 4, with the fingers engaged with packages. Fig. 6 is a sectional detail of one of the finger-carriers. Fig. 7 is a detail side elevation, partly in section, showing the clutch mechanism and tripping-lever for starting and stopping the package-actuating mechanism. Fig. 8 is a section of the clutch on line 8-8 of Fig. 7. Fig. 9 is a sectional detail showing the gluing mechanism and glue-holder. Fig. 10 is a vertical section of a weighing mechanism adapted for use in combination with the flap folding and sealing mechanism to actuate the same. Fig. 11 is a detail elevation at the rear of the weighing mechanism, showing the cam-lever which is engaged by one of the package-moving fingers and the connections for actuating the rock-shaft to open the scale-hopper valve. Fig. 12 is a detail, partly in section, on line 12-12 of Fig. 11. Fig. 13 is an enlarged detail elevation showing the clutch and some of the connections for driving and stopping the package-moving ring.

The carton filling and weighing mechanism shown is like that shown in Patent No. 716,007, dated December 16, 1902. It may be either a single-hopper machine or a double-hopper machine. The carton-moving ring is controlled by the tipping of the scale. The cartons to be filled are given a step-by-step movement along the track 1 by means of fingers 48, which project from the intermittently-rotating ring 84 to a position on the scale 90. If the carton has been partially filled through a preliminary feed, it will receive the remainder of its load through the hopper 91 while on the scale. If a single-hopper machine is used, the carton may receive its entire load while on the scale. The tipping of the scale-beam 92 under weight of the filled carton actuates mechanism which shuts off the feed of material to the carton and also causes the carrier-ring 84 to start. The filled carton is engaged by one of the fingers 48 and removed from the scale and pushed onto the table or plate 2, along which the cartons are carried in their passage to and from the several instrumentalities for sealing the upper end closing-flaps. When the scale tips, a reciprocating member 93 is caused to move in a direction to close the scale-hopper feed.

The carrier-ring 84 is driven by a pinion 94 on shaft 95, and shaft 95 is connected by a clutch 96, 96' and bevel-gears 97 and 98 with a shaft 99. The driving member 96 of the clutch is fast to shaft 95, and the upper member or shell 96' is fast to the hub of bevel-gear 97, but loose on shaft 95. In the inner periphery of shell 96' are a series of scalloped recesses 100, adapted to be engaged by a pawl 101 on the upper end of shaft 102 to lock the two members of the clutch together, and when so locked the shaft 95 will revolve and move the carrier-ring 84. A spring 103 tends to hold the pawl 101 thus engaged. On the lower end of shaft 102 is a dog 104, which when the reciprocating frame 93 is in its rearward position and the hopper-valve is open is engaged by a stop-lever 105 in a manner to hold the pawl-shaft 102 turned, so that the pawl 101 will be out of engagement with any of the recesses 100 and the shaft 95 will not turn.

When the reciprocating frame 93 moves forward to close the scale-hopper valve, a pro-

jection on the side of the frame will by its engagement with wedge-arm 107 and by engagement of said wedge-arm 107 with arm 112 push the sliding pin 108 to the left, as viewed 5 in Fig. 13, thereby causing the lug 109, which is carried by the sliding pin 108 and is in engagement with arm 110 of stop-lever 105, to turn stop-lever 105 on its pivot 111 and disengage the stop-lever from the dog 104, thereby 10 by allowing spring 103 to throw pawl 101 into engagement with one of the recesses in shell 96', and the pinion 94 is caused to revolve and move the carrier-ring 84. Carried on shaft 95 is an eccentric cam 113, which 15 when said shaft has partially completed a revolution will by its engagement with arm 114, projecting from sliding pin 108, turn said sliding pin 108 on its axis far enough to turn said arm 112 down out of engagement with wedge- 20 arm 107, and spring 115, which was compressed when the sliding pin 108 was pushed by the sliding frame 93, will expand and push said sliding pin in the reverse direction back into the position shown in Fig. 13, bringing the stop-lever 25 105 down into position to again intercept the dog 104 at the end of the revolution of shaft 95. When the dog 104 is thus intercepted, the two members of the clutch will be disengaged and the rotation of pinion 94 and of the carrier- 30 ring 84 will be stopped, the pinion 104 having made one complete revolution. After the eccentric cam 113 has moved around far enough for the stop-lever 105 to drop down into its intercepting position the said cam will before 35 the end of its revolution permit spring 115 to turn sliding pin 108 on its axis, so as to bring arm 112 back into the position shown in Fig. 13 ready to be engaged by wedge-arm 107 at the next feed-valve-closing movement of the 40 reciprocating frame 93, the wedge-arm 107 having been turned down out of its engaging position, as will be hereinafter described, so that arm 112 may be brought up into position. 45 There are various forms of mechanism by which the scale-hopper valve may be closed and the carrier-ring actuated by the tipping of the scale-beam and the valve opened again when a package is brought to the scale. The 50 mechanism shown in the drawings is operated by compressed air and is as follows: In one end of a double cylinder 116 is a piston whose stem 117 is connected with the forward cross-head of the reciprocating frame 93, and in 55 the other end of said cylinder is a piston whose stem 118 is connected with the rear cross-head of the reciprocating frame 93. The two cross-heads are connected together by side rods, which, together with the cross- 60 heads, constitute what is called the "reciprocating frame." The double cylinder 116 consists of two cylinders placed end to end, their outer ends being open. Between the two pistons is an air-chest 119, connected with a 65 compressed-air chamber and having ducts

which lead into the two members of the double cylinder 116. Moving in the air-chest 119 is a piston-valve 120, which as it rises and falls admits air-pressure alternately to the opposite chambers 121 and 122 of the cylinder 116, and thereby drives the pistons 117 and 118 and moves the reciprocating frame 93 to open and close the scale-hopper valve. Piston-valve 120 is connected by a rod 124 and crank 125 with a rocker-shaft 126, which 70 actuates the said piston. A torsion-spring 127 tends to rock said shaft 126 in a direction to pull down the piston-valve 120 and thereby apply the air-pressure to drive the reciprocating frame 93 in a direction to close the 80 scale-hopper valve. This tendency is resisted by the engagement of a stop-lever 128, fixed to the rock-shaft with the head of the pivoted vertical tripping-lever 129, whose lower end strikes against the end of the short 85 arm of the horizontal lever 130. When the scale beam tips under weight of a load, the hook 131 on the scale-beam engages the long arm of lever 130 and tips it up, releasing the lower end of vertical lever 129, so that the 90 rock-shaft 126 is allowed to turn under pressure of spring 127. The stop-lever 128 rides down along the side of the curved head of lever 129 and throws forward the lower end of lever 129, so that it stands above the reduced 95 rear portion of lever 130. The mechanism for rocking the shaft 126 in a direction to lift the piston-valve 120 and apply the pressure to move the reciprocating frame rearwardly and open the scale-hopper valve is actuated by the 100 moving carrier-ring 84 and is as follows: A cam-lever 132 is pivoted at 133 to the fixed ring 134. When the carrier-ring 84 moves, one of the fingers 48 rides over the cam-lever and turns it down. The movable end of said cam-lever is connected by a link 135 with the lever 136, which is fast to clutch-disk 137 on rocker-shaft 126. Disk 137 forms the driving member 105 of a clutch and engages with disk 138, which is slidable on shaft 126 but rotates with it. 110 Projecting from the side of disk 137 is a beveled tooth 142, which engages with a beveled notch 143 in the side of disk 138. Disk 138 is keyed to rocker-shaft 126, so as to slide thereon, but not to turn except with the said 115 shaft. A torsion-spring 139, which is of greater power than spring 127, tends to lift cam-lever 132 and hold it in contact with carrier-finger 48, and when the clutch-disks 137 and 138 are in engagement with each other it 120 turns the rock-shaft 126 in a direction to lift the piston-valve 120 and cause the reciprocating frame to move rearwardly and open the scale-hopper valve. A yoke-lever 144, fulcrumed to the under side of the fixed ring 134, 125 is engaged with the sliding disk 138 of said clutch by pins 145, which project from arms 146 of said lever 144 into the groove 147 in the periphery of disk 138. Said lever 144 is also connected by a link with the lower end 130

of the pivoted upright lever 141, which extends up into the path of the reciprocating frame 93, which operates the scale-hopper valve. A spring (not shown) normally holds 5 the upright lever 141 in a position to keep the disk 138 near enough to disk 137 for the tooth 142 to engage with notch 143. When the scale-valve is closed, the piston-valve being 10 down, the beveled face of tooth 142 will be toward the beveled face of notch 143 and upright lever 129 will rest on top of the notched 15 end of lever 130.

When the ring 84 begins to revolve, the 15 carrier-finger 48 rides on the inclined back of cam-lever 132 and depresses the said cam-lever against the tension of its spring 139, and by means of the link 135 and lever 136 the disk 137 is turned backward, causing its tooth 20 142 to ride out of the notch 143, pushing the disk 138 to one side and turning the upright lever 141 slightly on its pivot and against the pressure of its spring. (Not shown.) After the ring 84 in its rotation has brought the 25 finger 48 to the top of the inclined back of the cam-lever the continued rotation of the ring will allow the cam-lever to be turned up by the spring 139 and turn the disk 137 in the reverse direction, bringing the tooth 137 again into alignment with the notch 143, and the 30 spring which presses on upright lever 141 will throw lever 141, so as to bring the tooth 142 into engagement with notch 143. The continued pressure of spring 139 after the clutch-disks are in engagement with each 35 other will cause the rock-shaft 126 to turn in a direction to lift the connecting-rod 124 and move the piston-valve upward, and thereby actuate the reciprocating frame to open the scale-valve. The tension of spring 139 must 40 be strong enough to overcome the torsion-spring 127, which tends to rock the shaft 126 in a direction to pull down the piston and close the scale-valve. When the rock-shaft 45 126 has partially turned under the influence of spring 139, the pin 140 rides up along the head of lever 129 on the opposite side from stop-lever 128 and turns lever 129 far enough to disengage it from the upper side of lever 50 130. The forward end of lever 130 will then 55 drop and raise the rear end high enough to prevent the lever 129 from again moving forward under the action of lever 128 farther than to engage the rear end of lever 130 until said lever 130 is tipped by the scale-beam 59 92 under a load. When the reciprocating frame moves rearward, it engages upright lever 141 and turns it up far enough to disengage the clutch-disks 137 and 138 from each other, thus releasing the rock-shaft 126 from 60 torsion of the spring 139 and allowing it to respond to the spring 127. The stop-lever 128, which engages lever 129, prevents the rock-shaft 126 from turning far enough to 65 shift valve 120 until the lever 129 is disengaged from the end of lever 130 by the tip-

ping of the scale-beam. When the scale-beam is tipped by a load, the lever 129 will be disengaged from the end of lever 130, and the lever 129 being free to turn the torsion of spring 127 will turn rock-shaft 126 and 70 cause piston 120 to move down and admit pressure to close the scale-hopper valve.

The sealing mechanism comprises means for moving the package along on the table a certain distance for each cycle of operation, 75 means for engaging and partially spreading the two side flaps during such movement, a finger which engages and folds the rear-most of the end flaps, mechanism which then engages and folds the advancing end flap down over the said first folded or rear end flap, and means for spreading farther outward the two side flaps, and a carrier which moves the package with flaps thus spread beneath gluing mechanism, and mechanism which then turns 80 85 over and seals the two side flaps.

The mechanism for moving the packages after they are delivered by the carrier of the weighing and filling machine onto the table 2 90 will be first described.

Mounted on the guide-rods 45 are the sliding blocks 67. Centered at 8 to the sliding block 7 is an oscillating lever 9. Fixed to one end of lever 9 is an upright finger-carrying arm 13, to which the package-moving fingers 10 are attached. The other end of said lever 9 is formed with a slot 11 to engage a stud 12, which projects from the sliding block 6. On the upright arm 13 are projections 14, in which are held adjustable stop-screws 15, 95 which limit the arc of oscillation of lever 9. The stop-screws are so adjusted that when the fingers 10 are in their outward position, as in Fig. 4, the hooked ends will be outside of the path of movement of the packages, and when 100 turned into their inward position, as in Fig. 5, they will be in position to engage the package. Mounted also on the guide-rods 45 are sliding blocks 6' 7', carrying an oscillating lever 9' and having package-moving finger 10' 105 and other connected parts similar to the package-carrying finger 10 and connected parts just described.

Projecting from sliding block 6 is a boss 16, which is connected with boss 16', projecting from block 6', by a rod 17. Pivoted at one end on a stud mounted in boss 16' is a connecting-rod 18, the other end of said connecting-rod being pivoted to one end of a lever 19. The other end of said lever 19 is fixed 115 to a rock-shaft 20, which is journaled in the frame 21 and bracket 22. Fixed on the end of rock-shaft 20, which projects beyond the bracket 22, is a lever 23, to the outer end of which is pivoted one end of a connecting-rod 24. The other end of said rod 24 is pivoted 120 to the clutch-disk 25 by means of a crank-pin 26. Clutch-disk 25 is loosely mounted on shaft 27, which is driven by pulley 28 on shaft 31, through spur-gears 29 and 30. (See Fig. 130

- 1.) Fixed to shaft 27 is a flanged hub 32. Between the flange 35 of hub 32 and the disk 25 is a ratchet-wheel 33. Said ratchet-wheel has an annular flange 34, which loosely fits 5 around the outside of the flange 35 of hub 32. Friction-washers 36 37, preferably of leather, are placed on the two faces of the flange 35. On the outer side of the washer 37 is a clamp-ring 38. The washers and flange are 10 pressed between the ratchet-wheel 33 and clamp-ring 38 by means of screws 39, thus binding the ratchet-wheel to the flanged hub frictionally, so that the ratchet will normally revolve with the hub.
- 15 Pivoted to the disk 25 is a dog or pawl 40, adapted to engage with ratchet 33. A spring 41 tends to press the pawl into engagement with the ratchet, and when so engaged the disk 25 will revolve. The pawl is, however, 20 normally held out of such engagement with the ratchet by means of a stop 42, which engages with a pin 43, projecting laterally from the heel 44 of the pawl. The stop 42 is carried by a laterally-oscillatory arm 45, which 25 is fast to the vertical rock-shaft 46. Said rock-shaft 46 has fixed thereto a finger 47, which projects into the path of the package-moving fingers 48, carried by the rotating carrier connected with the weighing and pack-30 age-filling machine, Figs 1 and 7.
- When one of the package-moving fingers 48 on the weighing-machine engages the finger 47, the shaft 46 is turned, thereby causing the arm 45 to swing laterally, so as to with-35 draw the stop 42 from engagement with the pin 43 on the heel of the pawl. When the stop 42 is thus disengaged, the pawl responds to the pressure of spring 41 and engages with the ratchet 33, causing the disk 25 to rotate, 40 as already described. As soon as the package-moving finger 48 has passed from engagement with finger 47 a torsion-spring 49 turns rock-shaft 46 in the reverse direction, there-45 by swinging arm 45 back again, so that the stop 42 is in position to engage the heel of the pawl and trip the pawl out of engagement with the ratchet at the end of one revolution. A staple 50 is preferably used to limit the 50 swinging movement of the arm 45.
- 50 When the disk 25 revolves as just described, it actuates the crank-pin 26 and the link and lever connections to reciprocate the sliding blocks 6 7 6' 7' forward and back one stroke. In the forward stroke, which carries the car-55 tons one step forward, the blocks 6 6', being directly connected with the rod 17, will have an initial movement before the blocks 7 7', thereby turning the levers 9 9' until the rear stop-screws 15 15' strike the sliding blocks, 60 as shown in Fig. 5, and bringing the bent ends of the fingers 10 10' into engagement with the packages. Then the sliding blocks 7 7' will also begin to move forward, carrying with them the fingers 10 10', which pull

the packages along with them during the re- 65 mainder of the forward stroke. During the last half of the rotation of disk 25 the sliding blocks will be moved rearwardly. The friction of blocks 7 7' on the rods will be sufficient to retard the rearward movement of the 70 said blocks until after an initial movement of blocks 6 6' far enough to turn the levers 9 9' sufficient to bring the forward stop-screws 15 15' into engagement with the sliding blocks and throwing the fingers 10 10' outward, after 75 which all the blocks will slide rearward into the position shown in Fig. 4 ready to be moved into engagement with another package when the carrier again moves.

As already stated, when the package is car- 80 ried forward by the finger 10, which is the first to engage it, the side flaps are partially spread out and the rear flap is first folded and then the forward flap is folded. The mechanisms for performing these operations 85 will now be described.

Projecting rearwardly and upwardly from the upper part of the frame of the machine are the supporting bracket-arms 51 51, in which is journaled the rock-shaft 52. Fast 90 to the rock-shaft 52 is an arm 53, having at the end a finger 54, which is inclined downwardly and forwardly. Surrounding the rock-shaft 52 is a spiral spring 55, one end of which is fast to the shaft and the other end of which 95 is fast to the arm 51. The tension of the spring is such as to tend to throw the finger 54 downwardly. Also fast to the rock-shaft 52 is a short lever, the outer end of which engages, by means of a swiveling pin 60, a 100 block 58, through which slides a rod 59. The lower end of said rod 59 is pivotally connected with the connecting-rod 18. Fast to rod 59 is a stop-collar 61, which, during the latter part of the rearward movement of the connecting-bar 18, engages the block 58 and raises the finger-bearing arm 53 against the 105 pressure of the spring 55.

During the first part of the advance move- 110 ment of the rod 18 the movement of the rod 59 and its stop-collar 61 permits the rock-shaft 52 to turn under pressure of spring 55, and therefore to turn down the finger 54. If a package 3 is in position, the finger 54 will engage the rear flap 62 and fold it down. The 115 downward movement of the finger-bearing arm 53 is limited by the finger 63 engaging with a stop-pin 64 on bracket-arm 51. After the stop-pin is thus engaged the continued movement of the rod 18 will cause the rod 59 120 to slide through the block 58.

Journaled on the rock-shaft 52 on opposite sides of the finger-bearing arm 53 are arms 65 66, carrying at their outer ends flap-spread- 125 ing fingers 67 68. Springs 69 70 tend to press the fingers 67 68 downwardly. A cross-bar 71 above the finger-bearing arm 53 connects the fingers 67 68. This cross-bar rests on top

of arm 53, so that when arm 53 rises it lifts the arms 65 66 and the fingers carried thereby and prevents the fingers 67 68 from moving down under pressure of springs 69 70 until the finger-bearing arm 53 moves down.

When the arm 53 and its finger 54 move down to turn in the rear flap, the fingers 67 68 will also be turned down under the pressure of their springs, and the forward ends of the fingers 67 68, which are beveled on their outer edges, enter between the side flaps 72 and spread them slightly apart, so as to prevent them from interfering with the folding of the rear flap.

15 A stop-finger 73 engages the stop-pin 64 and limits the downward movement of the spreading-fingers 67 68. The stop is preferably so adjusted as to stop the downward movement of the spreading-fingers before the 20 stop-finger 63 engages with the pin to stop the downward movement of the folding-finger.

Secured to a bracket 75, carried by the frame, is a flap folding and spreading plate 74, which is made tapering and upwardly 25 curved toward its projecting end to engage with and fold the flap on the advance side of the carton. It is also so shaped as to engage the two side flaps and turn them down farther than they have already been turned by 30 the fingers 67 68. The plate 74 is at such an elevation that the carton can pass under it while the side flaps are laterally extended.

Journalized in the bracket 75 is a shaft 76, carrying a glue-feed roll 77, which revolves in 35 a glue-pan 78. Secured to the upper side of bracket 75 is a scraper 79 to remove the surplus glue. Carried by the shaft 27, already described, are the gluing-rolls 80 81, which engage and glue the laterally-extending side 40 flaps when they pass beneath them. The spreading-plate 74 extends beneath the glue-pan 78, so as to retain the flaps in their laterally-extended position until they are engaged by the gluing-roll.

45 After the carton passes the gluing-roll the side flaps are engaged by the guide-plates 82 83, which turn in and fold the two side flaps.

As already stated, the weighing and package-filling machine has a step-by-step movement, and at each period of movement one of the carton-moving fingers 48 on the weighing-machine engages the finger 47 and through the intermediate mechanism causes the sealing mechanism to go through one stage of movement. At the first step after the carton has been brought onto the plate 2 the rear carrier-fingers 10 move the carton to a position short of engagement with the gluing-roll, during which movement the rear and front 55 flaps will be folded and the side flaps extended. At the next period of movement the fingers 10' will engage the carton and move it beneath and past gluing-rolls. After passing the glu-

ing-rolls the succeeding packages will engage and push forward those in advance until they 65 pass between the guides, which fold the side flaps and carry them as much farther as may be desired before removal.

What I claim is—

1. In a machine for closing the flaps on the 70 upper end of filled cartons, mechanism which moves the filled cartons in an upright position in a horizontal path, a rearwardly-projecting arm pivoted above the path of movement of the filled cartons, said arm being pivoted to 75 oscillate in a vertical plane and being provided with a downwardly-turned flap-folding finger, mechanism which swings the flap-folding finger forward in the direction of movement of the carton into engagement with the rear flap 80 on the upper end of the carton, and means by which the carton-moving mechanism controls the starting of the flap-folding mechanism.

2. In a machine for closing the flaps on the 85 upper end of filled cartons, carton-moving mechanism, a rearwardly-projecting arm having a finger which overhangs the path of movement of the filled carton, said arm being pivoted so as to oscillate in a vertical plane, mech- 90 anism controlled by the carton-moving mechanism to swing the said flap-folding finger downward and forward into engagement with the rear flaps of the carton, and spreaders controlled by the movement of the said end-flap- 95 folding arm to spread the side flaps before the folding of the said rear flap, substantially as described.

3. In a machine for closing the flaps on the 100 upper end of filled cartons, a reciprocating slide which carries carton-moving fingers, a rearwardly-projecting arm having a flap-fold- 105 ing finger which overhangs the path of move- ment of the filled carton, said arm being pivoted so as to oscillate in a vertical plane, a spring which tends to turn said arm and finger downward, a rod connected with said slide and having a stop which engages said flap- 110 folding arm to hold the finger above the path of the carton and which is moved by said slide in its forward movement with the carton so that the flap-folding arm yields to the pressure of its spring and causes the finger to fold the rear flap, the said connecting-rod and stop being actuated by the rearward movement of 115 the said slide to again raise the flap-folding arm, substantially as described.

4. In a machine for closing the flaps on the 120 upper end of filled cartons, carton-moving mechanism, a rock-shaft having secured thereto a rearwardly-projecting arm having a flap-fold- 125 ing finger which overhangs the path of movement of the filled carton, a spring which tends to turn said rock-shaft in a direction to swing the flap-folding finger downward and forward, rearwardly-extending arms jour-

naled on said shaft on opposite sides of said flap-folding arm having wedge-fingers adapted to engage and spread the side flaps when moved downward and having springs which 5 tend to swing said arms downward, the movement of said side arms being controlled by the said flap-folding arm, a movable stop controlled by the movement of the carton-carrier to prevent the rock-shaft from yielding to its 10 spring until the said carrier moves, said stop being moved by the forward movement of the carrier to permit said flap-folding finger to move into engagement with the rear end flap and permit the side fingers to engage and 15 spread the side flaps, substantially as described.

5. In a machine for closing the flaps on the upper end of a carton, carton-moving mechanism, a rearwardly-projecting arm having a 20 flap-folding finger which overhangs the path of movement of the carton, said arm being pivoted so as to oscillate said finger in a vertical plane, mechanism controlled by the moving carrier to swing the flap-folding finger 25 downward and forward into engagement with the rear flap of the carton, vertically-swinging arms hung at opposite sides of said end-flap-folding arm, and whose movement is controlled by the movement of the said end-flap- 30 folding arm, said side arms being provided with wedge-fingers which partially spread the side flaps, and a rearwardly-extending tapering arm which engages the forward carton-flap and folds it over the first folded flap and 35 spreads outward and two side flaps, substantially as described.

6. In a machine for handling cartons, a slide, means for reciprocating said slide, a rearwardly-extending arm pivotally connected 40 with said slide and provided with a finger which points transversely of the path of movement of the carton, mechanism actuated by the slide in the first part of its forward movement to swing said arm and bring the said finger transversely of the path of movement of 45 the carton, the slide in the latter part of its forward movement drawing the said finger forward, and mechanism actuated by the rearward movement of the slide to swing said arm 50 and finger outward in the first part of its movement and then move them rearward, substantially as described.

7. In a machine for handling cartons, two reciprocable slide-blocks movable on parallel 55 guides, driving mechanism connected with one of said slide-blocks, an oscillating lever fulcrumed intermediate its ends to the other slide-block, one end of said lever having a slot which engages with a pin on said driven slide-block, the other end of said lever having fixed thereto an arm which extends rearwardly outside of the path of movement of said slide-blocks, said arm having a carton-moving fin-

ger which points transversely inward, stops carried on opposite sides of said lever, and 65 adapted to alternately engage with the block to which the lever is fulcrumed and limit the turning movement of said lever and cause it to then move with the slide-block.

8. A machine for filling and closing cartons 70 having weighing mechanism including a scale, mechanism for filling the carton, mechanism for closing the flaps which form the top of the filled carton, an intermittently-moving carrier which moves the cartons to the scale 75 and from the scale to the top-closing mechanism, means by which the tipping of the scale controls the starting of the carrier, and means by which the moving carrier controls the starting of the top-closing mechanism. 80

9. In combination with a carton filling and weighing machine, a scale, an intermittently-moving carton-carrier, which successively moves the cartons to the scale and carries them from the scale, means by which the tipping of the scale controls the starting of said carrier, mechanism for closing and sealing the flaps which form the top end of the carton, mechanism which moves the filled packages from the place where they are deposited 90 by the carrier of the weighing-machine, to positions for receiving the operations of the closing and sealing mechanism, driving mechanism and mechanism having clutch connection therewith which actuate the flap closing 95 and sealing mechanisms and carton-moving mechanisms connected therewith to each perform its part of the operation of moving, folding and sealing one carton at each cycle of movement, arresting mechanism which 100 disengages the said clutch at the end of each cycle of movement, mechanism actuated by the movement of the carrier of the weighing-machine to release said arresting mechanism from the clutch, and means for again engaging 105 said clutch, whereby the carton weighing and filling mechanism controls the closing and sealing mechanism to complete the closing and sealing of one carton for every new carton that is filled and weighed, substantially as described. 110

10. In a machine for handling cartons and giving them a step-by-step movement along a track, a reciprocating head, a lever pivoted to the reciprocating head carrying an arm 115 which extends rearwardly outside of the path of movement of the carton and provided with a finger at its rear end which points transversely of the path of movement of the carton, and mechanism actuated by the initial rearward movement of the head to move the said finger away from the path of the carton and actuated by the initial forward movement to draw the finger inward transversely of the path of movement of the carton and mechanism which retains the finger in the last-men- 120 125

tioned position during the forward movement, substantially as described.

11. In combination, weighing mechanism, mechanism for filling cartons, mechanism for closing the flaps which form the top end of the filled carton, an intermittently-moving carrier which moves the cartons from the scale to the top-closing mechanism, and means

by which the tipping of the scale controls the starting of the top-closing mechanism.

In testimony whereof I have affixed my signature in presence of two witnesses.

WILLIAM H. DOBLE.
